TIME CONTROLLED ANNUNCIATOR

John H. Grayson, Lynwood, Calif., assignor to
 Grayson Heat Control, Ltd., Lynwood, Calif., a
 corporation of California

Application September 29, 1936, Serial No. 103,161

1 Claim. (CL 161—23)

This invention pertains generally to annunciators, and while its principles may be embodied in apparatus designed for many specific uses it is here shown for illustrative purposes as applied 5 to a clock adapted more particularly for kitchen purposes.

The cooking of various foods requires the attention of the cook at various times for inspection purposes or to discontinue the cooking. 10 While an experienced cook knows approximately how long before her attention to the cooking will be required, she is apt, by reason of other distractions, to unconsciously prolong the period to the detriment of the food and sometimes to the 15 extent of its being spoiled by burning or over-cooking.

My present invention is designed to announce to the cook by a suitable signal the fact that her attention is required, the length of time elapsing 20 before the signal is given being dependent upon a predetermined setting of the apparatus.

More specifically my invention aims to provide an annunciator of the character indicated which will be simple in construction, which will consist 25 of a minimum number of parts, which will be economical to manufacture and easy to manipulate by the user, and which will be accurate, reliable, and durable in operation.

The preferred embodiment of my invention, 30 which has been chosen for illustrative purposes, is shown on the accompanying drawing.

Referring to which:

Fig. 1 is a front elevation of the apparatus;

Fig. 2 is a side elevation with the case shown 35 in section so as not to obscure the mechanisms;

Fig. 3 is a sectional view on the line 3—3 of Fig. 2;

Fig. 4 is a plan view with the case shown in 40 section similarly to Fig. 2; and

Fig. 5 is a sectional view on the line 5—5 of Fig. 2.

On the drawing, reference character 6 indicates generally the face of a clock, the mechanism of which is enclosed in the case 7, the entire assembly in the present instance being adapted to be mounted in a back panel 8 of a kitchen stove or in any other suitable support. The clock mechanism itself may be of the spring motor or electric motor type, an electric motor 9 being here illustrated. The clock train may consist of the usual pinions, gears, and other necessary mechanism, the details of which form no part of my present invention and are not here 55 illustrated except so far as may be necessary to

an understanding of the application of my invention thereto.

Immediately behind the dial of the clock there is mounted upon the motor driven shaft 11 a minute dial 12, provided on its face with minute 5 graduations 13 which are visible from the front of the clock through an opening 14 in the clock dial. This minute dial is rotatably mounted on and frictionally connected with the shaft 11 so as to be rotatable thereby and also be capable 10 of manual adjustment relatively thereto. While any suitable frictional driving connection between the shaft and the minute dial may be utilized, I have shown in the present instance the dial 12 as being cupped as shown at 15 to frictionally contact the face of a gear wheel 16 which, through the usual clock train (not shown) is positively driven from the shaft 11. Through this frictional connection, rotation of the shaft 11 is imparted to the minute dial 12 so that it normally rotates with the clock mechanism. 15

The minute dial may be independently adjusted by a knob 22 fixed on the shaft 23 which carries a pinion 24 meshing with the peripheral teeth of the dial 12. 20

A gear 16 with which the clock hands are associated is connected through an idler 17 with a pinion 18 on a shaft 19, on the outer end of which the time setting knob or button 21 is mounted. The gear 16 being also frictionally driven by the clock train, the setting of the hands 25 of the clock may be accomplished by turning the knob 21.

The device by which the signal, either audible or visible, is given may in some instances be of a 30 mechanical type although preferably an electric signal is employed and such type is here illustrated. The device as shown comprises an electric magnet consisting of a coil 25 connected in a circuit and the pole pieces 26 and 27, one of 35 which is disposed in proximity to a resilient magnetic armature 28 having one end anchored at 29 and the other end upturned at 31 to constitute a striker adapted to impact against a sounding board 32 of suitable material anchored 40 at one end as indicated at 33. Adjustment of the sounding board toward and from the striker for tone modulating purposes may be effected by adjustment of an abutment screw 34 projecting through the back of the case 7 into engagement 45 with the sounding board. Alternate current energization of the coil 25 will cause the armature 28 to vibrate and thereby in conjunction with the sounding board produce an audible signal. 50

In this instance the armature pieces of the 55

5 solenoid constitute the magnetic poles of the electric motor; consequently the pole pieces are being continuously energized and the armature 28 would continuously vibrate unless restrained. 10 For the purpose of preventing operation of the signal except at predetermined times I have made provision for controlling the operation of the signalling device from the minute dial 12. With this end in view the dial is provided near 15 its margin with a slot or groove 35 adapted upon rotation of the dial to be brought into alignment with a depending shoulder 36 formed on a bell crank lever 37 which is fulcrumed at 38 to an ear 39 carried by a member 41 of the clock frame. 20 The upper end of this lever is adapted to abut against and hold the armature 28 against the sounding board 32 in the position shown in the drawing when the shoulder 36 is supported upon the minute dial as shown in full lines in Fig. 2 but is adapted to retract into the dotted line 25 position shown in said figure when the slot 35 is brought into alignment with the shoulder 36. Movement of the lever from the full line position to the dotted line position of Fig. 2 is ensured by a leaf spring 42 which overlies the lever as shown.

In order to maintain the signalling device inoperative, irrespective of the position of the slot 35, I have provided a manually operable throw-out device comprising a cam shaped member 43 fixed on a shaft 44, on the outer end of which is mounted a knob 45. When this cam is turned to the position shown in full lines on Fig. 5, the high portion 46 thereof engages beneath a shoulder 47 formed on the lever 37 and holds the lever up against the sounding board. When the cam, however, is rotated to the dotted line position shown in Fig. 5, it is withdrawn from this shoulder so as to permit lever 37 to be urged 40 against the minute dial under the influence of the spring 42.

When no signal is required, the signalling device is held out of operation by the cam 43; but when the user desires to be signalled at a prede-

5 termined future time, the cam 43 is moved to inoperative positions and by manipulation of the knob 22 the minute dial is turned to bring the number corresponding with the number of minutes desired to elapse before the signal becomes effective into the center of the opening 14 in the clock dial. The minute dial is now rotated by the clock mechanism in the usual way to bring the slot 35 after a predetermined interval 10 for which the top has been set into alignment with the shoulder 36 whereupon the shoulder rides off the face of the dial into said slot, permitting the lever 37 to withdraw from the armature 28 whereupon the operation of the signalling device 15 is initiated. The device may be shut off by simply turning the knob 45 to again project the lever 37 into engagement with the armature 28.

10 The structural details illustrated and described are capable of considerable modification without departing from the essence of the invention as defined in the following claim.

I claim:

20 In a time controlled annunciator, the combination of a clock driven shaft, a minute dial frictionally connected to said shaft so as to be driven thereby and be adjustable relatively thereto, said dial being provided on one face with indicia and being provided with a control slot spaced from the perimeter of the dial, an annunciating device 25 including a vibrator, an angular lever fulcrumed in proximity to said disc and provided with a shoulder adapted to rest against the rear face of the dial whereby the free end of said lever is maintained in the path of said vibrator to preclude actuation of the vibrator, said shoulder being adapted to enter said control slot in the dial when aligned therewith to thereby permit withdrawal of the end of said lever from the path of said vibrator, a spring urging said shoulder toward said dial and manually operable means 30 engageable with said lever for positioning the lever in vibrator holding position independently of said disc.

JOHN H. GRAYSON.
